UNITED STATES PATENT OFFICE.

ANTON MAZZANOVICH, OF LOS ANGELES, CALIFORNIA.

WINDOW AND DOOR CLAMP.

Application filed August 3, 1921. Serial No. 489,472.

To all whom it may concern:

Be it known that I, ANTON MAZZANOVICH, a citizen of the United States, residing at Los Angeles, in the county of Los Angeles and State of California, have invented new and useful Improvements in Window and Door Clamps, of which the following is a specification.

My invention relates generally to theatrical scenery, and more particularly to a clamping device that is utilized for clamping the frame of a door or window to the frame or upright battens of a flat or upright piece of scenery that is intended to represent a wall, partition, or like structure.

The principal objects of my invention are to provide a relatively simple and practical form of clamp that may be easily and quickly applied for use and which will be effective in clamping the frame of a door or window to a flat without the use of nails, screws, or like fastening devices.

With the foregoing and other objects in view, my invention consists in certain novel features of construction and arrangement of parts that will be hereinafter more fully described and claimed and illustrated in the accompanying drawings, in which:

Figure 1 is a perspective view of a door frame in position upon a flat, and showing my improved clamp in position thereupon.

Fig. 2 is an enlarged horizontal section taken on the line 2—2 of Fig. 1.

Fig. 3 is an elevational view looking in the direction indicated by the arrow 3 in Fig. 2.

Fig. 4 is an enlarged horizontal section taken on the line 4—4 of Fig. 3.

Referring by numerals to the accompanying drawings which illustrate a practical embodiment of my invention, 10 designates a flat or upright piece of scenery, and which flat includes a pair of upright battens 11, and which latter are preferably arranged at the sides of an opening for a door or window. In the present instance I have shown my improved clamp applied to a door frame, which latter includes a pair of stiles 12, a lintel 13, and the usual side and top casings 14.

My improved clamp includes a substantially U-shaped frame 15 preferably formed of metal and having its inner edges bent outwardly to form retaining lips 16. This frame is secured in any suitable manner to the rear or outer face of the door stile 12,

and removably positioned in said frame and retained therein by the lips 16 is a metal plate 17 with which is formed integral the outer end of the short leg of a horizontally disposed L-shaped bolt 18. The longer leg 19 of this bolt occupies a position parallel with the plate 17, and said longer leg is threaded in order to receive an internally threaded sleeve 20, the surface of which is preferably knurled in order that it may be readily manipulated.

Arranged for rotation upon the outer end of the sleeve 20 and held retained thereupon by a collar 21 that is secured to the said sleeve, is a ring 22 with the outer portion 70 of which is formed integral two or more outwardly projecting ears 23, and which latter, when the device is in use, are adapted to bear directly against the rear face of the adjacent batten 11.

In the use of my improved door or window clamp, the frame of the door or window is inserted in the opening in the flat 10 between the battens 11, and after the parts have been positioned so that the casings lie directly against the front face of the flat, the plate 17 is inserted downwardly into the frame 15, after which the sleeve 20 is rotated so that it moves outwardly on the threaded portion 19 of bracket 18. As 85 this operation continues, the ears 23 on ring 22 will bear against the rear face of the adjacent batten, and as the sleeve 20 is tightened, the batten 11 and the casing 14 will be pressed together, with the result that 90 the parts will be very firmly clamped to each other and the door or window frame retained in proper position upon the flat. Obviously by reversing the operations just described, the door or window frame may 95 be easily and quickly removed from the flat.

A clamping device of my improved construction is comparatively simple, may be easily and cheaply produced, and is effective 100 in eliminating much of the time and labor ordinarily involved in assembling scenery, and particularly the mounting of door and window frames in flats or like upright pieces of scenery.

It will be understood that minor changes in size, form and construction of the various parts of my improved window and door clamp may be made and substituted for those herein shown and described without 110

departing from the spirit of my invention, the scope of which is set forth in the appended claims.

I claim as my invention:

5. 1. A clamp for connecting a frame to a flat, comprising a substantially U-shaped support, an L-shaped bolt having the end of its shorter leg removably positioned in said support, the longer leg of said bolt being 10 threaded, and an internally threaded sleeve mounted on the threaded portion of said bolt.
15. 2. The combination with a flat and a frame that is adapted to be removably positioned therein, of a supporting member on said frame, a plate removably positioned in said supporting member, a horizontally disposed L-shaped bolt secured to said plate, and an internally threaded sleeve mounted 20 on the threaded portion of said bolt and adapted to engage a part of the flat.
20. 3. The combination with a flat and a

frame that is adapted to be removably positioned therein, of a supporting member on said frame, a plate removably positioned in 25 said supporting member, a horizontally disposed L-shaped bolt secured to said plate, an internally threaded sleeve mounted on the threaded portion of said bolt, and a flat 30 engaging member loosely mounted on the end of said sleeve.

4. A clamp for connecting a frame to a flat, comprising a substantially U-shaped support, an L-shaped bolt having the end of its shorter leg removably positioned in 35 said support, the longer leg of said bolt being threaded, an internally threaded sleeve mounted on the threaded portion of said bolt, and a flat engaging member loosely arranged on the outer end of said sleeve. 40

In testimony whereof I have signed my name to this specification.

ANTON MAZZANOVICH.
